EASTERN MANUFACTURING COMPANY, OF BOSTON, MASSACHUSETTS, A COR-
PORATION OF MASSACHUSETTS.

PAPER-FEEDING MEANS FOR SIZE-TUBS.

1,390,997.

Specification of Letters Patent. Patented Sept. 20, 1921.

Application filed January 4, 1921. Serial No. 435,047.

To all whom it may concern:

Be it known that we, ARTHUR L. LITTLE and GEORGE W. VEROV, citizens of the United States; residing at Brewer, in the county of Penobscot and State of Maine, have invented new and useful Improvements in Paper-Feeding Means for Size-Tubs, of which the following is a specification.

This invention has relation broadly to tub 10 sizing paper.

In the process of tub sizing paper, it has been customary to pass the sheet of paper from the initial drier through a bath of sizing material, and then to pass the sheet 15 through a second drier or drier section. The paper is fed through these instrumentalities at high speed, approximately 265 feet a minute, and the machine tenders have to be very expert in order to pass the end of a 20 sheet from the first drier through the tub sizing apparatus to the second drier on account of the high speed at which these several instrumentalities are operated. On account of the width of the sheet of paper 25 and of the necessity of guiding the paper without lateral deviation as it passes from one instrumentality to the other, it is customary to form on the end of the sheet what is known as a "tail," namely a relatively narrow 30 marginal strip, the remainder of the sheet being cut or torn away, so that the machine tender by grasping this tail is able to present it to the succeeding instrumentalities near the ends of the rolls by which it is gripped. The sheet must be thus tailed, as it were, because of the impossibility of presenting the entire width of the sheet to the several instrumentalities without tearing or otherwise forming plaits or wrinkles. It 35 is practically impossible for the machine tenders to handle the end of the web when it is of the usual or normal width. Thus, not only is the passage of the end of a sheet from one instrumentality to the other difficult 40 because of the high speed at which the paper is caused to travel, but this operation is furthermore attended by danger to the machine tender. The end of the paper must be passed between rolls which are moving at 45 high speed and there is constant danger of the machine tender getting his fingers or hand caught in the nip of the rolls. A slight carelessness on the part of the machine tender would cause the crushing of his hand 50

and arm, and has at times caused the loss 55 of life.

The object of the present invention is to provide means by which the paper may be passed through the tub sizing apparatus accurately and without danger to the machine 60 tender.

The tub sizing apparatus comprises ordinarily a tank or tub in which the liquid size is contained, and through which the paper is caused to travel, and squeeze rolls between 65 which the paper is passed for the purpose of expressing therefrom the surplus size.

In accordance with our invention, the sizing machine is provided with a carrier which cooperates with at least one of the 70 squeeze rolls for the purpose of receiving the tail on the on-coming sheet and carrying it to a point where it will be gripped by the nip of the rolls.

On the accompanying drawings,—

Figure 1 represents more or less diagrammatically the dry end of a paper machine, a sizing apparatus, and the end of the drier to which the paper is subjected after passing through the tub.

Fig. 2 represents on a larger scale the tub sizing apparatus.

Fig. 3 represents a plan view of one end thereof.

Fig. 4 illustrates the end of an on-coming sheet on which a tail is formed to enable it to be passed from the paper machine through the sizing apparatus to the final drier or second stack.

It will be understood that the drawings 85 are more or less conventional and diagrammatic, that the phraseology which is herein employed is for the purpose of description rather than of limitation, and that various changes may be made in the apparatus as 90 herein described without departing from the spirit and scope of the invention as defined in the claims.

Referring to Fig. 1, A indicates the dry 100 end of a paper machine and includes the necessary drying rolls and drier felts which are ordinarily employed for removing from the initially formed sheet a predetermined amount of the moisture therein contained, so that the sheet is capable of sustaining its 105 own weight in its passage from the said dry end to the sizing tub or sizing apparatus. B indicates conventionally the end por-

tion of the second drier or stack through which the paper is passed after being sized, and it will be understood that this second drier likewise comprises the necessary heated 5 rolls, drier felts and other instrumentalities which are ordinarily employed in a drier used for this purpose. Between these two driers is located, as ordinarily, a sizing apparatus which is indicated as a whole at C. 10 This apparatus comprises a tub or tank 10 which may be supported upon suitable side frames 11, and it is so formed as to contain a bath of the liquid size which it is desired to use. The bottom of the tub comprises the 15 horizontal wall 11 and the inclined wall 12. Ordinarily such a tank or tub is provided with a vertical cross partition 13 dividing the tub into the main compartment 14 and an overflow compartment 15. The usual squeeze 20 or press rolls are indicated at 16, 17, which are similar to those ordinarily employed and which are arranged over the tub, with the lower portion of the roll 16 dipping into the bath contained in the tub. The top roll 17 25 is adjustable by the ordinary means not shown. As thus far described, the sizing apparatus does not differ from those ordinarily in use, being provided as usual with the guide roll 18 under which the sheet passes 30 for immersion in the bath, and the guide roll 19 over which the sheet is passed on its way to the second drier or stack.

Heretofore, with an apparatus as thus far described, at least two men have been necessary to transfer the end of a sheet of paper from the first drier A through the sizing apparatus to the second drier B. When the on-coming end of the sheet of paper reaches the end of the first drier, the attendant usually by means of a knife slits one side edge to form on the sheet a tail b, as shown in Fig. 4, removing and throwing aside a greater portion of the body of the sheet which has thus been slit. When the tail is 45 of sufficient length, it is grasped by the attendant and thrust under the guide roll 18 into the tub. A second attendant reaches into the bath, grasps the tail, and drawing it under the lower squeeze roll 16 presents it to the nip of the rolls 16, 17. As he accomplishes this, the first attendant runs from his previous station to a point at which he may grasp the tail of the sheet, pass it over the guide roll 19, and carry it into the 50 second drier B and present it to the rolls and drier felts of that drier. These operations must be accomplished with great expedition, for, as we have stated, it is ordinarily the practice to so operate the various instrumentalities that the sheet is traveling at a rate of about 200 to 265 feet per minute, 55 265 feet being the apparent maximum at which the operators may work with safety.

We have provided the sizing apparatus 60 with means for receiving the tail of the

sheet and carrying it to a point where it may be gripped by the nip of the squeeze rolls, thereby eliminating the necessity of employing more than one operator or machine tender and removing the danger that 70 has heretofore attended the presentation of the tail of the sheet to the nip of the rolls. 75

By reference to Figs. 2 and 3 of the drawing, it will be noted that we have provided an endless belt which is indicated as a whole 80 at 20. This belt is narrow in width, being only wide enough to receive the narrow tail along one side edge of the sheet of paper. The belt is passed under guide rolls 21, 22, which are immersed in the sizing solution or compound in the tub, and the shafts of which are loosely journaled in suitable brackets as indicated at 23, 24, respectively. The upper stretch of the belt engages the peripheral 85 surface of the roll 16 for a considerable distance, and thence passes around a roll 25, the shaft 26 of which is journaled in brackets or frames 27. This roll 25 is located between the rolls 16 and 17 and as close to the 90 nip thereof as is possible according to its diameter. After passing around the roll 25, the belt returns to the roll 21. The belt itself is preferably made of fabric or other equivalent material which will frictionally engage the tail of the paper. The belt may be caused 95 to move at the peripheral speed of the roll 16 by reason of its engagement with the roll, but, if desired, it may be driven in addition by a belt 28 passing around pulleys 30 and 31 secured to the roll 17 and the roll 25 respectively, the pulleys 30 and 31 being of 100 such relative diameter that the speed of travel of the carrier belt 20 is equal to the peripheral speed of the lower squeeze roll 16. Any suitable means may be employed for 105 tightening the carrier belt 20 so as to cause it to press against the peripheral surface of the roll 16 during the operation of carrying the tail of the paper through the sizing apparatus. It is rather desirable that, during 110 the normal operation of the sizing apparatus, the carrier belt should be released from the roll 16 so as to engage it only lightly, and consequently the belt-tightening means should be so constructed as to permit this 115 result. If, under ordinary conditions, the belt or carrier 20 presses too tightly against the roll 16, the paper may be marked. A belt tightener, which serves the purpose, is illustrated on the drawing, and comprises 120 a loosely-journaled roll 32 mounted in the ends of swing arms 33 pivoted upon a cross bar or cross shaft 34 the ends of which are mounted in the frame or bracket 27. This belt-tightening roll may be swung from the 125 position shown in Fig. 2, at which it bears by gravity upon the vertical stretch of the carrier belt 20 so as to tighten the belt and cause it to bear firmly against the squeeze roll 16, to the position shown in dotted lines 130

at which the belt is permitted to become slack or loosen so as only slightly to engage the squeeze roll 16 or the paper which is passing therearound.

5 In threading the paper through the sizing apparatus, the attendant forms on the paper the usual tail *b*, as shown in Fig. 4, and inserts the end under the roll 18 into the bath of sizing material, and grasping it carries it to a point where it will be gripped between the carrier belt 20 and the lower squeeze roll 16. The tail is then carried upwardly by the belt and the roll to a point where it is gripped by the nip of the rolls 16 10 and 17. The machine tender, as the tail emerges between the rolls 16, 17, on the left-hand side in Fig. 2, is able to carry the tail over the guide roll 19 and present it to the second drier. By this apparatus, which we 15 have thus described, it is possible for one attendant to thread or pass the paper from the first drier to the second drier without the necessity of manually presenting the tail to the nip of the squeeze roll, and it is also possible for one attendant or operative to accomplish what has heretofore required the services of at least two attendants.

It will be understood that various changes may be made in the apparatus as we have 30 herein illustrated and described it. Of course, while we have only shown one narrow belt for engaging the tail of the paper, this belt may be duplicated if desired, or, in other words, several still narrower belts 35 may be employed instead of a single belt as shown. The location of the various guide rolls for the carrier belt may be changed.

We have not attempted to illustrate in detail all of the various parts of the sizing 40 apparatus, including means for heating the sizing material, as these are well known and in common use.

What we claim is:—

1. The combination with the first and sec-

ond driers, and an intermediate sizing apparatus including squeeze rolls, of means for receiving the end of a sheet of paper and automatically carrying it under one of the squeeze rolls and presenting it to the nip of said rolls. 45

2. In a paper-sizing apparatus, the combination with a tank for containing the liquid sizing material and the squeeze rolls, of a carrier belt of adequate width to receive the tail at the end of an on-coming sheet of 50 paper, and arranged to pass such tail under the lower squeeze roll and to present it to the nip of the squeeze rolls. 55

3. In a paper-sizing apparatus, the combination with a tank for containing the bath 60 of liquid sizing material and upper and lower squeeze rolls for removing surplus size from the sheet, of a carrier belt partially immersed in the bath and having a portion to track against the lower squeeze 65 roll, and appropriate guide rolls for said carrier belt, of which one is immersed in the receiving end of the tank and another is adjacent the nip of the squeeze rolls. 70

4. In a paper-sizing apparatus, the combination with a tank for containing the bath of liquid sizing material and upper and lower squeeze rolls for removing surplus size from the sheet, of a carrier belt partially immersed in the bath and having a portion to track against the lower squeeze 75 roll, appropriate guide rolls for said carrier belt, of which one is immersed in the receiving end of the tank and another is adjacent the nip of the squeeze rolls, and 80 manually-operated belt-tightening means for causing said carrier belt to engage the said lower squeeze roll. 80

In testimony whereof we have affixed our signatures.

ARTHUR L. LITTLE.
GEORGE W. VEROW.
